[57] CLAIM

The ornamental design for a child safety belt, as shown and described.

DESCRIPTION

FIG. 1 is a front, top and end perspective view of the child safety belt showing my new design;
FIG. 2 is an end elevational view thereof;
FIG. 3 is an end elevational view thereof;
FIG. 4 is a rear elevational view thereof;
FIG. 5 is a front elevational view thereof; and,
FIG. 6 is a top plan view thereof, the bottom view being a mirror image of the top view shown in FIG. 6.

FIG. 1

FIG. 2

FIG. 3

FIG. 4

FIG. 5

FIG. 6
